UNITED STATES PATENT OFFICE.

WILLIAM PATTERSON, OF PHILADELPHIA, PENNSYLVANIA.

GARMENT HANGER.

Application filed July 1, 1926. Serial No. 119,861.

This invention has reference to garment hangers or clothes racks of the character described and illustrated in my U. S. Letters Patent #1,587,676, issued June 8, 1926, and 5 provides certain novel and useful improvements in the construction and operation of such devices.

One of the objects of the invention is to provide for a better and more positive actuation of the hanger arms, and a more simplified assemblage of the moving parts of the device as well as a more practical and economic construction.

In general, the invention provides an ornamental bedroom clothes tree or hanger of simple, sturdy, metal construction adapted to give a lasting dependable service and which can be folded up into a compact form when not in use. Additional advantages may be 20 apparent from the following detailed description of the invention, and from the annexed drawings showing one of the many possible embodiments wherein:

Figure 1 is a perspective view of a section 25 of a bedroom door with the device attached thereto.

Figure 2 is a horizontal section of the device as viewed from the top, with the parts enclosed in the casing.

Figure 3 is a longitudinal section of the device as viewed from the front, with the parts enclosed in the casing.

Figure 4 is a longitudinal section of the device as viewed from the side, the parts being 35 enclosed in the casng.

Figure 5 is a side view of the hanger in operative position, the parts being shown in section.

Figure 6 is a top view of the hanger in 40 operative position, the casing being shown in section.

Figure 7 is a sectional view taken along line 7—7 of Figure 5.

Figures 8, 9, and 10, are detail views. 45 In the drawings, 1 designates a section of a bedroom door to the inner surface of which is attached the casing 2 of the hanger. Fitting snugly within the casing and pivoting on pin 3 at its lower end is a support bar 4 having 50 at its free end a hook 5 which serves as a support for a suit-hanger and also as a finger grip for swinging the support bar into and out of the casing. A carrier bar 6 is supported by the support bar 4 and carries a plurality of article-holding elements, such as the hanger arms 7. In the present embodiment,

the carrier bar consists of a metallic tubular member having longitudinally spaced openings 8 on opposite sides and a vertical pivot pin 9 adjacent the outer end of each opening. 60 Each pivot pin has a hanger arm 7 loosely mounted thereon to swing freely through the adjacent opening 8, the latter being preferably shaped in conformity with the shape of the hanger arm. Support bar 4 is also of 65 hollow, metallic, construction and is adapted to house the carrier bar, the opposite sides of the support bar being provided with openings or cut-outs 10 to allow for the outward and inward swinging movement of the hanger 70 arms.

The carrier bar is arranged to slide within the support bar and is so coupled to the casing 2 as to be automatically shifted alternately back and forth as the support bar is raised and lowered. This shifting movement is effected simultaneously with the raising and lowering of the support bar by means of a U-shaped coupling 11, shown in detail in Fig. 10. On each side of its base, the coupling has a trunnion 12 and the arms of the coupling are also provided near their outer extremities with trunnions 13. Bearing openings 14 are located in the sides of the carrier bar and near the inner end of the latter to receive the trunnions 12 and the casing has its back wall provided with outstanding ears or lugs 15 having bearing openings to receive the trunnions 13, the arms of the coupling being so constructed as to be capable of being flexed inwardly toward each other to facilitate the placing of the trunnions 13 in the openings in the lugs. 85

The hanger arms are arranged in pairs of oppositely disposed units and an actuating mechanism is provided for moving the arms into operative position as the support bar is withdrawn from the casing. The actuating mechanism comprises a long and narrow flat bar or strip 16 of metal extending within the support bar for almost the entire length thereof, as shown in Fig. 5, and passing through the tubular carrier 6 and between the units of each pair of hanger arms. This operating bar 16 is free to slide and has affixed thereto in longitudinally spaced relation a plurality of hanger arm actuating members. Each actuating member comprises a pair of spring fingers 17—17' connected at one end by the portion 18 which is riveted or otherwise fastened to the underside of the flat operating bar 16. The fingers 17—17' extend longitudi- 100 105 110

nally of opposite sides of bar 16 with their flat sides presented to the edges of the bar and they are flexed to spring outwardly from the bar with their outer ends pressing against the inner surfaces of opposite hanger arms, as seen in Fig. 3. Hence, each hanger arm is subjected to the outward pressure of a spring finger which thus serves to swing the arm outwardly of the openings 8 and 10 in the carrier bar and support bar respectively, whenever such openings are brought into alignment by the shifting of the carrier bar.

When the support bar 4 is enclosed in the casing, the parts are positioned as shown in Figs. 3 and 4. The carrier bar 6, it will be observed, has been shifted forwardly within the support bar to the extreme limit permitted by the coupling 11 so that the openings 8 and 10 are relatively offset, with the hanger arms lying within openings 8 and retained therein against the outward pressure of the spring fingers 17-17' by the overlying portions or abutments 19 of the side walls of the support bar. The operating bar 16, which in the horizontal position of the support bar abuts with the casing as shown in Fig. 5, is likewise shifted forwardly in the vertical position of the support bar, being carried along with the carrier bar by reason of the friction grip of the spring arms 17-17' on the folded-in hanger arms. The extent of the forward shifting movement of the operating bar 16 is indicated by the spacing between the lower end 20 of the bar and the bottom of the casing, as seen in Figs. 3 and 4. It will be observed, also, that the support bar is cut away at 21 to avoid interference with the pivoted coupling 11. As the support bar is swung outwardly and downwardly of the casing, the carrier bar is gradually shifted toward the inner or pivoted end of the support bar by reason of the coupling 11 until a point is reached where the openings 8 and 10 are so nearly aligned as to permit the hanger arms to be moved outwardly thereof, under pressure of the spring fingers 17-17', so that the ends 22 are swung clear of the edges 23 of opening 10. This action occurs before the support bar has reached the limit of its downward travel and as the carrier bar continues to be shifted inwardly, the end 20 of bar 16 abuts with the back wall of the casing. This prevents further inward movement of the bar 16 and, hence, as the pivot pins 9 of the hanger arms move inwardly with the carrier bar and closer to the curved ends 24 of the spring fingers, the hanger arms are caused to stand out from the sides of the support bar, at right angles thereto and up against the rear edges 25 of the openings 10 which edges serve as abutments for limiting the backward swing of the hanger arms.

To fold up the device when the same is not in use, the support bar is simply swung up into the case, the carrier bar shifting auto-

matically to the outer end of the support bar during the upward movement of the latter and causing the hanger arms to swing into openings 8 as they are moved past the edges 25 of openings 10. The operating bar 16 does not move with the carrier bar until the hanger arms have been drawn inwardly enough to compress spring fingers 17-17' and to be firmly engaged by said fingers in a frictional grip sufficient to cause the bar 16 to move as a unit with the carrier bar. The movements of the parts are so timed that this shifting of the operating bar 16 occurs shortly after the initial movement of the carrier bar. The support bar is retained within the casing by a spring latch consisting of a spring tongue 26 struck up from the back wall of the casing and frictionally engaging the outer end 27 of the support bar.

From the foregoing it will be noted that the use of coiled or helical springs are avoided and that a smooth and moderate movement of the parts is obtained which lessens the strain and wear on the device and renders the same more dependable and lasting.

Having thus described the invention, what is claimed as new, is:

1. A garment hanger comprising a support, hanger arms pivotally mounted thereon, said arms being arranged in pairs of oppositely disposed units, a bar extending lengthwise of the said support and between the units of each pair of hanger arms, and a plurality of arm-actuating members carried by said bar in relatively spaced relation, each of said arm-actuating members comprising a pair of spring fingers flexed to spring outwardly of respectively opposite sides of the bar for engaging the said hanger arms, said support being slidable with respect to said bar to effect operative engagement of the spring fingers with said hanger arms.

2. A garment hanger comprising a supporting casing, a support bar having one end pivoted to the casing, a carrier bar slidable in said support bar and carrying a plurality of pivotally mounted article-holding elements, said support bar having side openings to allow for the outward and inward swinging movement of the said article-holding elements, means connecting the said carrier bar to the said casing to cause the carrier bar to be shifted alternately back and forth within the support bar as the latter is raised and lowered with respect to the casing, and a slidable operating member extending within and lengthwise of the said carrier bar and equipped with spring fingers arranged to engage and exert outward pressure on the said article-holding elements, and means for causing said member to remain stationary at a predetermined time during sliding movement of the said carrier bar, whereby the article holding elements are caused to travel relatively to the engaging spring fingers and

to be thereby swung outwardly to an operative position.

3. A garment hanger comprising longitudinally disposed relatively movable members, an article-holding element pivotally supported on one member and normally extending longitudinally thereof, and an actuating element slidably encased by the same member and disposed adjacent said article-holding element for movement longitudinally thereof during relative movement of the members, said actuating element serving to swing the article-holding element outwardly of its supporting member as it approaches the pivot of the article-holding element.
4. In a garment hanger, a pair of longitudinally disposed relatively movable members, an article-holding element pivotally supported on one member and extending longitudinally thereof, and a spring-tensioned element slidably encased by the same member and pressing outwardly against the article-holding element, said spring-tensioned element being adapted to swing the article-holding element outwardly of its supporting member as the pivot of the article-holding element is shifted towards the spring-tensioned element during the relative movement of the two members.
5. In a garment hanger, a pair of longitudinally disposed relatively slidable members, an article-holding element pivotally supported on one member and extending longitudinally thereof, a spring-tensioned element slidably encased by the same member and pressing outwardly against the article-holding element, said spring-tensioned element being adapted to swing the article-holding element outwardly of its supporting member as the pivot of the article-holding element

is shifted towards the spring-tensioned element during the relative slidable movement of the two members, and abutment means for limiting the outward swing of the said article-holding element.

6. In a garment hanger, a supporting member, a pair of oppositely disposed article-holding elements pivotally supported on said member for swinging movement outwardly thereof, said elements being normally disposed to extend longitudinally of the member, an actuating member between the said article-holding elements having spring arms pressing outwardly against the inner sides of the article-holding elements for exerting pressure on the latter, and means for shifting the actuating member relatively to the article-holding elements for causing the latter to swing outwardly of the support as their pivots approach the spring arms of the said actuating member.

7. A garment hanger comprising a supporting member, hanger arms pivotally mounted thereon and arranged in pairs of oppositely disposed units, and an actuating mechanism including a bar extending lengthwise of the supporting member and between the units of each pair of hanger arms and having thereon a plurality of diverging spring fingers, said bar being free to slide with respect to the supporting member to permit the spring fingers to be brought into operating engagement with the hanger arms by sliding movement of the supporting member with respect to said bar and means for effecting such sliding movement of the supporting member.

In testimony whereof, I affix my signature.

WILLIAM PATTERSON.
